Specification for Design.

Patented July 26, 1921.

Application filed December 20, 1920. Serial No. 432,118. Term of patent 14 years.

To all whom it may concern:

Be it known that I, HAMILTON T. HOWELL, a citizen of the United States, residing at New York, in the county of New York and State of New York, have invented a new, original, and ornamental Design for a Plate for Lighting-Fixtures, of which the following is a specification, reference being had to the accompanying drawings, forming part thereof.

Figure 1 is a perspective view of a plate for lighting fixtures, showing my new design.

Fig. 2 is a side view, showing the contour.

Fig. 3 is a cross sectional view taken on the line $x-x$ in Fig. 1.

I claim—

The ornamental design for a plate for lighting fixtures as shown.

HAMILTON T. HOWELL.
